COMBINED FINGER RING AND DOLL

Erin Libby, Hermosa Beach, Calif., assignor to Mattel, Inc., a corporation of California

Filed Dec. 12, 1967, Ser. No. 9,751

Term of patent 14 years

Int. Cl. D11—01

U.S. Cl. D45—10

Fig. 1

Fig. 2

Fig. 3

Fig. 4

Fig. 5

Fig. 6

I claim:

The ornamental design for a combined finger ring and doll, as shown.
